7 Claims. (Cl. 53—92)

1

This invention relates to the manufacture of paper crackers, commonly known as bon-bon crackers.

The main operations in the manufacture of a paper cracker have been firstly to roll together into cylindrical form a number of superimposed paper sheets, hereinafter referred to as a paper pack, and secondly to form two waist portions in the roller cylinder by crimping it at suitable positions inwards of the ends of the cylinder. The crimped waists serve to trap within the hollow centre portion of the cylinder a folded paper cap and/or other articles, hereinafter referred to as a "centre." Hitherto the first operation, that is, of rolling the pack to form a paper cylinder, has been effected by hand.

The waist forming or crimping operation has generally and for a long time been effected by looping a length of string around the portion of the paper cylinder to be waisted and closing the loop in the string so as to contract the cylinder by uniformly crimping the encircled paper.

The waist forming or crimping operation is usually referred to in the trade as the "tying" operation and the looped string method of waist forming will be so designated herein, although it is understood that the expression "tying" is a misnomer in that the looped string does not remain on the waist as a permanent "tie."

The "tying" operation using the looped string principle was originally performed by hand, and this hand-tying operation has been imitated substantially in machinery by means of which the two waists are made simultaneously, the crimping to form each waist being effected by means of a length of string extending between the outer ends of a pair of arms which rock in opposite directions so as each partially to embrace the paper cylinder and thereby to crimp the paper at the cylinder waist within the loop formed by the crossing halves of the length of string. During this "tying" operation the paper cylinder has been supported by cylindrical formers inserted into the opposite ends of the cylinder. It will be readily understood that the contraction due to crimping at the waists of the cylinder is accompanied by a shortening of the overall length of the cylinder and in order to compensate for this shortening the machines used have provided for an endwise translatory movement of the two string-connected pairs of arms during the loop-forming rocking movements of the arms, or have relied upon tension in the strings, aided by pressure from the formers, to cause the desired transverse motion of the strings. In practice automatic movement

2

of the strings to compensate for the shortening of the paper cylinder has been followed up on the part of the operator by moving inwardly and in an endwise direction the two end formers by which the cylinder is supported as the operator offers the cylinder to the tying strings.

The speed at which the known form of cracker "tying" machine can be operated is governed largely by the dexterity of the operator in offering the rolled paper cylinder to the tying strings and in retracting the cylinder after waisting, but also by the speed at which the paper cylinder can be rolled, as it is customary for the same operator both to roll and to "tie" a cracker as two separate successive operations.

It is an object of the present invention to provide a machine in which the paper pack is automatically rolled to cylindrical form prior to waisting by mechanical means, for example, by mechanism operating on the looped string principle, so that the forming and "tying" can be effected as a continuous operation. The output of the machine is not governed in this case by any manually effected operation, the machine being capable of completely forming and waisting many more crackers in a given time than can be made by separate successive hand forming and machine "tying" operations.

Another object of the present invention is to provide a machine for making paper crackers which incorporates a forming mechanism including a pair of axially aligned rotating cylindrical formers around which a flat paper pack is adapted to be rolled into cylindrical form by means of said formers as they are mechanically rotated in unison and a mechanism for simultaneously forming two waists in the paper cylinder by crimping of the paper and operating synchronously with the mechanically rotated formers, said formers supporting the paper cylinder at its opposite ends during the waist crimping operation and at least one of said formers being subsequently displaced endwise to permit of release of the waisted former-supported cylinder.

A further object of the present invention is to provide a machine for making paper crackers having the features above referred to and which incorporates mechanical means for displacing string-connected arms of "tying" assemblies in relation to the axially aligned formers of the forming mechanism, mechanical means to effect swinging of said string-connected arms to effect the "tying" of the supported paper cylinder, and mechanical means for displacing both formers simultaneously in opposite endwise directions to

release the waisted former-supported cylinder. Such a preferred arrangement readily lends itself to the construction of cracker making machine in which the forming mechanism is adapted to be displaced bodily between a position in which it picks up a paper pack and a position in which the waist crimping mechanism operates to form waists in a paper cylinder made from said paper pack and supported by the forming mechanism, said paper cylinder being formed automatically as the forming mechanism moves from the pack pick-up position to the waist-crimping position.

In a preferred embodiment, one end of a paper pack is adhered to the peripheries of a pair of axially aligned cylindrical formers by pneumatic suction or by means of mechanical or magnetic grippers and the formers are made to revolve as they move between the pick-up position and the "tying" position so as to wrap the paper pack around them to form a cylinder, the cylinder, after the "tying" operation, being discharged from the machine on the side thereof remote from that at which pick-up of the paper pack takes place.

In order that the invention may be more readily understood cracker making machines using the looped string principle of "tying" will now be described, with the aid of the accompanying drawings, wherein:

Figure 1 is a front elevation of one construction of machine, some parts being broken away for clearness,

Figure 2 is a cross sectional elevation on line II, II of Figure 1 and showing the formers in the tying position,

Figure 3 is an enlarged view, similar to Figure 2, showing the formers in the pack pick-up position,

Figure 4 is a pictorial, part-sectional view of one of the forming heads with some of the associated operating mechanisms,

Figure 5 is a longitudinal section through the forming head.

Figure 6 is a view similar to Figure 1, to an enlarged scale and showing some modifications of the operating mechanisms,

Figure 7 is a fragmentary view looking in the direction of arrow VII, Figure 6,

Figure 8 is a pictorial diagram to illustrate the mode of operation of the machines,

Figure 9 is a cross sectional view of an attachment for feeding a "centre" to the interior of a partially made paper cylinder and

Figure 10 is a plan view thereof.

In the machines illustrated in the accompanying drawings the forming mechanism and the "tying" mechanism are mounted on a common frame 1 which comprises a pair of cast side plates, 2, 3 rigidly interconnected by a number of cross bars 4, 5, 6, 7, 8 and 9 and by a transverse beam 10, the bars 5 and 6 being arranged at the same level and disposed symmetrically above and in relation to a transversely and horizontally disposed main shaft 11. The shaft 11 is journaled in a pair of brackets 12, 12 supported by the beam 10. Near the opposite ends of main shaft 11 two combined crank discs and face cams 13, 13 are mounted and to these are pivotally attached connecting rods 14, 14 which are also connected to a pair of laterally spaced slides 15, 15 so as to reciprocate said slides 15, 15 over vertical guide slides 16, 16 mounted on the frame side plates 2, 3. Between the vertically guided slides 15, 15 there extend, parallel to the main shaft 11, a pair of round axles 17, 17 which are arranged at the

same horizontal level and one behind the other in a fore and aft direction. Upon each of the axles 17 are mounted two rockers 18, 18 each carrying a curved-end arm 19, the four rockers 18, 18 thus supporting two pairs of curved arms 19, 19 so that an arm 19 on a rocker 18 on one axle 17 is paired with an arm 19 on a rocker 18 on the other axle 17.

The arms 19 are not attached directly to the rockers 18 but pass through pivot pins 20 which are free to swivel in holders 21, said holders 21 being provided with slots 22 which receive the straight parts of the arms 19. The holders 21 are mounted on shanks 23 which are secured to the rockers 18 and the pivoted arms 19 are held erect by means of tension springs 24 having their opposite ends anchored to collars 25 on the arms 19 and collars on the holder shanks 23, the arrangement being such that the arms 19 can swing toward the centre of the machine against the light resistance offered by the springs 24, as hereinafter described.

The rocker axles 17, 17 have secured thereto arms 26 carrying rollers 27 which are adapted to roll along cam tracks 28 provided on opposite sides of a fixed cam plate 29 mounted in an erect position on a bracket 30 borne by a narrow platform 31 supported horizontally by cross bars 5 and 6. The lower portions of the cam tracks 28 are straight and vertically disposed and serve to maintain the string arms 19 in their open positions, but the upper portions of said cam tracks 28 are formed with humps which cause the string arms 19 to swing into their closed positions.

Above the level of the two rocker axles 17, 17 which extend between the vertically movable slides 15, 15 are mounted two forming heads 32, 32 each of which carries one of a series of interchangeable cylindrical mandrels 33, 33. Two mandrels 33, 33 of the same size are adapted to be mounted in the forming heads 32, 32 so that the mandrels 33, 33 are aligned along an axis which is parallel to the axles 17, 17 and to the main drive shaft 11.

The two forming heads 32, 32, which always remain in transverse axial alignment, are mounted so as to be capable of being traversed backwards and forwards, with a rectilinear movement, in the fore-and-aft direction, and when at the aft end of travel the two mandrels 33, 33 are situated in a position, hereinafter termed the "tying" position, immediately and centrally above the two axles 17, 17 (see Fig. 2). The position of the two forming heads 32, 32 when at the fore end of their travel (see Fig. 3) will be hereinafter referred to as the pick-up position.

The fore-and-aft movements of the forming heads 32, 32 and the transverse movements of at least the mandrels 33, 33 for the purpose herein-after more particularly described, may be effected by any suitable means, such as by cam-operated linkages or by pneumatic devices. Suitable link mechanism for effecting the two movements synchronously is illustrated and comprises mounting each forming head 32 on the forward end of a substantially horizontal beam 34, the rear end of which is pivotally connected to the upper end of a control lever 35 which by its lower end is pivotally mounted on an axle 36 journaled horizontally and transversely in the two side plates 2, 3 of the frame of the machine. Intermediately of its length the beam 34 is pivotally connected to the upper end of a rocker 37, the lower end of which is pivotally supported by a layshaft 38 provided on a level lower than and parallel to the

main drive shaft 11. A roller 39 mounted on the rocker 37 is maintained, by spring biasing of the rocker if desired, in contact with the edge of a disc cam 40 secured to the main shaft 11, so far that as the main shaft 11 revolves the disc cam 40 regulates the forward movement and effects the rearward movement or effects both forward and rearward movement of the forming head 32. The pivotal connections and the effective lengths of the rocker 37, beam 34 and control lever 35 are so arranged that these three elements form an articulated link system which imparts a substantially straight-line to-and-fro motion to the forming head 32, and the disc cam 40 which co-operates with the rocker 37 is contoured so as to cause the forming head 32 to dwell for a short period at the pick-up position and for a longer period at the "tying" position. The two rockers 37, 37 controlling the two forming heads 32, 32 are cross connected by a rigid stabilising bar 41.

The transverse movement of each mandrel 33 is effected by detachably mounting the mandrel 33 on a screwed spigot 42 projecting from the front part of a cylindrical two-part block 43 which is slidable within a hollow cylinder 44 fixed to the rocker 37 (see Figs. 4 and 5). Between the two halves of block 43 is a ring 45 and this ring 45 is connected, by pins 46 passing through guide slots 47 in the cylinder 44, to links 48, 48 pivoted to rockable levers 49, 50, which are secured to a vertical pivot pin 51 carried by the head 32. The upper lever 50 is formed with an extending arm 52 which is provided at its outer end with a roller 53 which is adapted to roll along the edge of a cam plate 54 carried on a rockable arm 55 which is pivoted on a bracket 56 mounted on the adjacent side plate 2 or 3. The arm 55 is connected by a pivoted link 57 to another rockable arm 58, mounted also on bracket 56, and carrying a roller 59 which is in contact with the track of the appropriate face cam 13 on the main shaft 11, thereby causing the block 43 and ring 45 and the mandrel 33 mounted thereon to perform an endwise movement independently of the cylinder 44 of the forming head 32. The link 57 is pivotally attached to arm 55 by means of a pivot 60 adjustable within a slot 61 in one limb of the arm 55, so that the throw of the arm 55 can be varied to regulate the amount of transverse movement of the mandrel 33 according to the length of paper cracker being made.

The mandrel 33 and its associated mounting block 43 are adapted to be rotated relatively to the hollow cylinder 44 by providing the block 43 with a rod-like extension 62 which through the intermediary of a sliding key 63 maintains operative connection with a toothed pinion 64 which is held in the outer end of the cylinder 44 against endwise movement whilst free to rotate. A rack-bar 65 mounted by its front end on a pivot 65a carried by the adjacent side plate 2 or 3 is maintained by spring tension means (not shown) in constant mesh with the pinion 64 so that as the forming head 32 moves forwards and backwards the stationary rack bar 65 rotates the pinion 64 and with it the slidable block 43 and the mandrel 33 spigoted thereon.

Interposed between the arm-supporting axles 17, 17 of the "tying" mechanism and the forming heads 32, 32 a substantially horizontal table 66 is mounted which has a pair of transversely spaced slots 67, 67 (see especially Fig. 8) up through each of which a pair of the string-connected arms 19, 19 can be swung, so that when the transversely aligned forming heads 32, 32 are

dwelling in the "tying" position, the two arms 19, 19 constituting a pair move in opposite directions so as partially to embrace one of the mandrels 33. The movements of the forming heads 32, 32 and of the "tying" mechanism are synchronised so that both ends of a paper cylinder 68 supported between the inwardly directed mandrels 33, 33 of the forming heads 32, 32 are waisted simultaneously by crimping of the cylinder 68 which is effected by the two looped strings 69, 69 carried by the swingable "tying" arms 19—19.

When the forming heads 32, 32 are at the fore end of traverse they over-run the forward edge of the table 66 so as to dwell for a short period above the rear end of a flap 70 which is mounted for hinged movement about the transverse cross bar 4 located adjacent to the forward edge of the flap 70. On this flap 70 at least one side lay 71 is adjustably mounted and against this the operator (or a mechanical feeder) deposits a paper pack in its flat unrolled condition, so that when the flap 70 is hinged about the cross bar 4 by means of a push-rod 72 co-operating with a bell-crank lever 73 which carries a roller 74 rolling on the edge of a cam 75 on the main drive shaft 11, one margin of the paper pack is lifted into contact with the peripheries of the aligned mandrels 33, 33 carried by the stationary forming heads 32, 32, the push rod 72 being resiliently attached to the lever 73 by a spring 76 and stirrup 77, so that intimate contact between paper pack and mandrels is secured.

Each mandrel 33 is hollow and the periphery thereof is pierced by a series of small holes 78 communicating with the bore 79 of the mandrel 33 so that a pneumatic suction can be applied through the holes 78 to cause the margin of the paper pack contacting with the mandrel 33 to adhere thereto. The rod-like extension 62 of block 43 is made hollow and constitutes a continuation of the bore 79 of mandrel 33, a union fitting 80 being mounted on the outer end of said extension 62. To the union fittings 80, 80 associated with the two mandrels 33, 33 are attached pipelines 81, 81 leading to a common control valve 82 mounted on the beam 10. This control valve 82 is connected to a suitable suction pump (not shown) and the valve 82 has a plunger 83 which is reciprocated by a cam 84 mounted on the main shaft 11. The main shaft 11 is driven by a chain drive 85 from an electric motor 86 and speed reduction unit 87 carried on a platform 88 supported horizontally by the cross rods 8 and 9.

Above and parallel to the rocker shafts 17, 17 an ejector shaft 89 is mounted and upon this shaft 89 one, or preferably, as shown, a pair of rocking ejector arms 90, 90 are mounted. These ejector arms 90, 90 lie between the two pairs of string arms 19—19 and are adapted to be swung up from positions beneath the table 66, through the slots 67, 67 therein so as to contact with and knock the waisted paper cylinder 68 to the rear, that is, the discharge end of table 66. The ejector shaft 89 is rocked at the appropriate time during the sequence of operations of the machine by means of linkage 91 moved by a cam 92 on the main shaft 11. If desired the cam 92 may be shaped so as to cause the ejector arms 90, 90 to swing up into contact with the paper cylinder 68 supported on mandrels 33, 33 and to dwell in that position while the mandrels 33, 33 are being withdrawn from the open ends of the paper cylinder 68.

The table 66 is supported by vertically adjustable transverse bars 93, 94, so that the height of

the table 66 can be readily altered according to the size of mandrel 33 being used.

The basic operations of the machine will be readily understood from Figure 8, which shows diagrammatically the two mandrels 33, 33 supporting the paper cylinder 68 at the tying position. The mandrels 33, 33 partake of three movements of which one is a clockwise rotary movement E effected simultaneously with forward traverse, that is, in direction B to bring the mandrels 33, 33 above the rear end of flap 70, see Figure 3. The flat paper pack 95 is diagrammatically indicated in Figure 8 where it is shown as deposited by hand or by mechanical means on the flap 70 with one edge abutting the riser portion 69a of the forward end of table 66. While the mandrels 33, 33 are partaking of movements E and B the flap 70 is lifted by the push rod 72 and associated means in the direction of arrow C, so that as the mandrels 33, 33 come to rest at the pack pick-up position the marginal edge of paper pack 95 is presented to the peripheries of the mandrels 33, 33, the control valve 82 being cam operated to open at the same moment so as to cause the marginal edge of the pack 95 to adhere to the mandrels 33, 33.

As the forming heads 32, 32 retreat in direction D (Figure 8) toward the "tying" position the mandrels 33, 33 are caused to revolve in unison and anticlockwise, that is, in direction A, so as to roll the paper pack indicated at 95 into the form of a cylinder indicated at 68 having its opposite ends supported by the mandrels 33, 33. The terminal margin of the paper pack 95 has a band of pressure-sensitive or other suitable adhesive for the purpose of securing the paper pack in the cylindrical form. By the time the forming heads 32, 32 have arrived at the "tying" position (see Figures 2 and 8) the two slides 15, 15 carrying the transverse arm-supporting axles 17, 17 have been elevated to the limit of ascent by the crank devices provided, and the rockers 18, 18 are then made to rock so as to swing the string-connected pairs of arms 19-19, this tying movement being caused by the rollers 27, 27 on the arms 26, 26 on axles 17, 17 contacting the humps in the cam tracks 28, 28 of the fixed cam plate 29 as the slides 15, 15, ascend.

During the "tying" operation the paired string-connected arms 19-19 move endwise in an inward direction to compensate for the shortening of the cylinder 68 as the waists are formed, this inward movement following automatically the positive inward movement F of the mandrels 33, 33 by means of face cams 13, 13 and associated linkages, so as to ensure that well-defined corners are produced between the centre portion of the cylinder 68 and the crimped waists.

After the paper cylinder 68 has been "tied" by the looping of the strings 69 the tying arms 19-19 swing back and down through the slots 67, 67, in the table 66 so that the mandrels 33, 33 can be moved apart in directions G, clear of the waisted cylinder 68. As already mentioned the ejector arms 90, 90 may dwell in contact with the mandrel-supported cylinder 68, while the mandrels 33, 33 are withdrawn before said arms 90, 90 move to knock the released cylinder 68 to the rear end of table 66. During the return traverse of the mandrels 33, 33 or during the period of dwell thereof in the tying position the flap 70 is swung down in direction H to set it in readiness to receive another paper pack 95.

Figures 6 and 7 illustrate two modifications of the machine illustrated in Figures 1 to 5,

namely means for positively displacing the cracker tying arms to compensate for shortening of the paper cylinder 68 during waisting and an alternative mode of operating the ejector arms. The first modification comprises slidably mounting the string arm rockers 18-18 on the axles 17, 17 and mounting rollers 96, 96 on the rockers 18-18, said rollers 96, 96 being adapted to roll over cam plates 97, 97 fixed on opposite sides of the machine. As the axles 17, 17 are bodily moved the rollers 96, 96 ride on to the humps 98, 98 of the cam plates 97, 97 at the end of the tying operation and the rockers 18-18 and their string arms 19-19 are moved inwards against the opposition of compression springs 99, 99 encircling the axles 17-17 and interposed between said slideable rockers 18-18 and collars 100, 100 pinned on said axles 17-17. The second modification comprises rocking the ejector arms 90-90 by means of a push-rod 101 connected to a lever 102 pivoted on the bracket 30. The lever 102 carries a roller 103 which is contacted by another roller 104 on one of the axles 17, 17 as the axles near the limit of descent, and an adjusting screw 105 to regulate the swing of the ejector arms 90-90.

The paper pack 95 from which the cylinder 68 is made usually consists of at least two sheets of paper, between which a so-called snap, that is, a frangible strip carrying an explosive substance, is often interposed. The inner sheet or a third sheet is often made smaller and stiffer than the outer sheet so as to form in the cracker a stiffened middle portion which not only preserves the final form of the cracker but also constitutes a housing for protecting a folded paper hat and/or other articles generally enclosed in a cracker and herein referred to as the "centre." The reinforced middle portion of the cracker may thus be formed as the pack 95 is rolled to make a cylinder 68. The articles to be enclosed in the cracker may be made up into a unitary packet which is lightly adhesively secured to the topmost sheet of the pack so that the packet is rolled up within the cylinder as it is being formed.

Alternatively, one or more loose articles may be deposited within the partly-rolled cylinder by the use of any suitable feeding means, one form of which is illustrated in Figures 9 and 10 of the drawings. In this arrangement a bracket 106 is mounted on each forming head cylinder 44 and in these two brackets is journaled for rotation a cross shaft 107. Parallel to the cross shaft 107 and mounted in the same brackets 106, 106 is a fixed axle 108 which supports a hopper 109. At the discharge end of the hopper 109 one of an interchangeable series of curved grippers 110 is mounted and a complementary gripper 111, also one of an interchangeable series, the gripper 111 being suspended from the shaft 107 for rocking therewith. On a projecting end of the shaft 107 is a normally downwardly extending finger 112 which during movement of the forming heads 32, 32 toward the tying position contacts with a cam plate 113 secured to a lever 114 pivoted on a pin 115 mounted on a stationary part of the machine, such as one of the rack bars 65. During movement of the forming heads 32, 32 toward the tying position the finger 112 trips the lever 114, so that the grippers 110 and 111 remain in the mandrel-embracing positions and thus serve to hold the rolled pack around the mandrels 33, 33. The inner marginal edge of the paper pack 95

is accessible to the suction openings 73 of the mandrels 33, 33 through the bottom opening 116 and when the pack 95 has been partially wrapped around the mandrels 33, 33 the "centre" is dropped by any suitable means into the hopper 109 and thence into the partly made paper cylinder. The grippers 110 and 111 maintain their embrace of the rolled paper cylinders and the enclosed ends of the mandrels 33, 33 during the waist tying operation. As the forming heads 32, 32 move after cylinder waisting from the tying position toward the pack pick-up position the finger 112 is tripped by a roller 117 on lever 114, thereby rocking the shaft 107 and with it the gripper 111 so as to allow the ejector arms 90-90 to knock the released cracker cylinder 68 to the discharge end of table 66. The tripping of the lever 114 by the finger 112 is effected against the resistance of a tension spring 118 anchored to a pin 119 on the rack bar 65 and during the tripping of the finger 112 by the lever 114 the lever abuts a stop 120 on the rack bar 65.

I claim:

1. A machine for making paper crackers, comprising in combination, a frame, a substantially horizontal table on said frame and having therein a pair of slots arranged in fore-and-aft direction, means on said table for locating a flat paper pack adjacent the front part thereof, two tying assemblies mounted on said frame for vertical bodily movement beneath said table with the string-connected pairs of arms of said tying assemblies aligned with the two table slots, a pair of axially aligned formers movable in unison on said frame at right angles to the planes of swinging of the tying arms and between a position above said slots and a position in which the formers lie opposite an edge of the front part of said table adjacent said paper pack locating means, means for causing the paper pack to adhere to the formers, means on said frame for mechanically rotating the aligned formers in unison as they are displaced together in a fore-and-aft direction above the platform to roll said paper pack into a cylinder around the formers, means on said frame for effecting swinging of the string-connected arms of the tying assemblies up through the platform slots to effect waist-crimping of the paper cylinder at two places simultaneously while said cylinder is supported on the formers and while said formers dwell above the platform slots and then for swinging said arms down through the platform slots and clear of the upper face of the platform, and means on said frame for retracting the formers by endwise displacement to release the waisted cylinder.

2. A machine according to claim 1, wherein the formers are adapted to move inwards during the tying operation to consolidate the middle portion of the cracker cylinder, between the two waists formed therein.

3. A machine according to claim 2, wherein the string-connected tying arms are mounted so as to permit them to move inwardly to compensate for approach together of the waists during the waist-forming operation.

4. A machine according to claim 1, having means on the frame to assist discharge of the waisted cylinder from the tying position after release from the forming mechanism.

5. A machine according to claim 1, having means mounted above the table for feeding a "centre" as herein defined into a partly-rolled paper pack.

6. A machine for making paper crackers, comprising a frame, a forming mechanism on said frame including a pair of axially aligned cylindrical formers and including pneumatic means to cause the marginal edge of a paper pack to adhere to said formers, an elevatable platform on said frame for supporting said paper pack and for lifting said paper pack into contact with said formers, mechanical means on said frame for rotating said formers in unison, a mechanism on said frame for simultaneously forming two waists in the paper cylinder by crimping of the paper, means on said frame for operating said waist-crimping mechanism synchronously with the mechanically rotated formers, a driving mechanism on said frame for bodily reciprocating the forming mechanism between a position in which it picks up said paper pack from off said table when elevated and a position in which the waist-crimping mechanism operates on the paper cylinder, said paper cylinder being formed automatically as the forming mechanism moves from the pack pick-up position to the waist-crimping position and being supported at its opposite ends by the aligned formers during the waist-crimping operation, and means for displacing endwise at least one of said formers after the waist-crimping operation to permit of release of the waisted former-supported cylinder.

7. A machine according to claim 6, including a waist-crimping mechanism comprising two "tying" assemblies including two pairs of string-connected arms mounted for swinging movement in opposite directions so as to loop the strings around the paper cylinder to form simultaneously a pair of waists therein by crimping the paper, and including mechanical means on the frame for displacing the string-connected arms of the "tying" assemblies in relation to the axially aligned formers of the forming mechanism, mechanical means on said frame to effect swinging of the string-connected arms to effect the "tying" of the supported paper cylinder, and mechanical means on said frame for displacing both formers simultaneously in opposite endwise directions to release the waisted former-supported cylinder.

EDGAR HARRISON.
